UNITED STATES PATENT OFFICE.

ADOLF STOLLENBERG, OF NEW YORK, N. Y.

VEGETABLE-CUTTING MACHINE.

1,369,202.

Specification of Letters Patent. Patented Feb. 22, 1921.

Application filed July 10, 1919. Serial No. 309,929.

To all whom it may concern:

Be it known that I, ADOLF STOLLENBERG, a citizen of Germany, residing at New York, in the county of New York and State of New York, have invented certain new and useful Improvements in Vegetable-Cutting Machines, of which the following is a specification.

The present invention relates to vegetable cutters and has for its principal object to provide a device by means of which different kinds of vegetables or fruit, such as potatoes, onions, carrots, etc., apples, pineapples, etc., may be readily and conveniently cut up into pieces of various shapes and sizes without crushing.

A further object of my invention is to provide such construction as will enable the handling of the cutter by unskilled persons.

And a still further object of my invention is to provide a construction which will eliminate waste in material.

With these and other objects in view my invention consists in the arrangement, combination and construction of parts more specifically described hereinafter and as set forth in the appended claims.

In the accompanying drawings in which similar reference characters denote corresponding parts, Figure 1 is a side elevation of my new cutter; Fig. 2 is a top plan view thereof; Fig. 3 is a section along line 3—3 of Fig. 2 showing the parts as used in a full sized machine; Fig. 4 is a cross section on line 4—4 of Fig. 2; Fig. 5 is a cross section on line 5—5 of Fig. 3 showing a portion of the vegetable or food feeding mechanism in one position; Fig. 6 is a similar section as Fig. 5 showing the said mechanism in a different position; Fig. 7 is a cross section on line 7—7 of Fig. 3; Fig. 8 is a front view of two cutters adapted to coöperate with one another to cut the vegetables or fruit into pieces of a certain shape; Fig. 9 is a section on line 9—9 of Fig. 8; Fig. 10 is a section on line 10—10 of Fig. 8; Fig. 11 is a section on line 11—11 of Fig. 8 and Fig. 12 is a sectional view of a cutter which may be used in conjunction with the two cutters shown in

Fig. 8 or only with the circular cutter shown 50 therein.

The cutting device forming the subject of the present invention comprises a casting made of a lower section 10 and an upper section 11 and which, at one side, is formed to 55 a receptacle 12 extending throughout the entire length of the casting and serving to receive the vegetable or fruit to be cut. One end of said receptacle is closed while the other end opens toward knives to be applied 60 to said end and which will be hereinafter fully described. The upper section serves as a cover for said receptacle and is removably fixed to the lower section by screws 13 or otherwise. Near the open end of the receptacle 65 said cover is provided with a charge opening 14 surrounded on its outside with upwardly projecting flanges 15 forming a sort of hopper. The part 11' of said cover extending laterally beyond the receptacle is 70 formed on its inner face with a longitudinal semi-cylindrical groove 16 to serve as a hood for a worm spindle 17 to be hereinafter fully described. The said part 11' is also provided at its ends with semi-cylindrical ex- 75 tensions 18, 19 which, in coöperation with correspondingly sized and shaped grooves 20, 21 in the lower section, constitute bearings for said spindle 17. At the open end of the receptacle the casting is provided with a 80 groove 22 and the cover with a groove 23 which grooves coincide with one another and are open at one side of the casing as at 9. These grooves serve to form a socket, the object of which will be hereinafter explained. 85

The spindle 17 which extends below the hood 16 formed by the cover is hollow. Extending through the hollow of said spindle is a shaft 24 which, with its ends, projects outwardly from underneath the hood. At 90 the open end of the receptacle the shaft 24 is adapted to receive a circular cutter 25 of any suitable construction. In the present embodiment of my invention the cutter is in form of a circular disk having one or more 95 spirally shaped radially extending grooves 26 and a corresponding number of blades 27 suitably fixed to the rear of the disk so as to

project with their edges 27' over one edge of said grooves as shown in Fig. 11. This cutter is removably secured in place to the shaft. It has a radially extending recess 28 near the spiral blades 27 to form a socket. This socket serves to removably bear in itself a member 29 adapted to be tightened to the disk 25 by a nut 30 (Fig. 8) working on the end of the shaft 24. This member may, according to the work desired, have different functions. It may be either in form of a bar fitting snugly in said recess 28 and having a smooth inner surface. In this case it merely serves as a closure for the opening or recess 28. Or it may be formed with blades 31 suitably fixed in said bar and forming a cutter 32 as shown in Fig. 12. The shape and size of the bar forming the cutter 32 conform with those of the member 29 so that when required the knife 32 may be substituted for the plain bar 29. The hub portion of the member 29 and that of the knife 32 is ring shaped as at 33 to fit around the outer end of the shaft 24 and to be tightened in position by the nut 30.

Movably mounted in the receptacle 12 of the casting is a member 34 the front face 34' of which may be roughened. This member in cross section conforms with the cross section of the receptacle and is of a height to project up to about the inner face of the upper section with a narrow clearance between itself and the walls of the receptacle and cover. This member 34 serves to feed the vegetables or fruit placed into the receptacle toward the knife or knives and serves thus as a pusher or feeder. In order to allow of the vegetables or fruit being cut into slices or pieces of different thicknesses, the pusher is moved intermittently and the extent of its periodical forward thrust is regulated by suitable means to be described.

This pusher is formed at its rear with an extension or bolt 34² which is adapted to engage a socket 35² formed in a lateral extension or arm 35' projecting into the receptacle 12 from a nut 35 working on the worm spindle 17. When the spindle 17 is revolved the nut will be fed forwardly or rearwardly as the case may be and the pusher will advance or retreat.

The worm spindle 17 has a cylindrical extension 17' at the end of which the closed end of the receptacle is located, which extension projects outwardly from the casting. The extension 17' is provided with two shoulders 17², 17³ of which the shoulder 17² is adapted to rest against the inner wall and the shoulder 17³ is adapted to rest against the outer wall of the bearing formed by the semi-cylindrical grooves 18, 20 in the lower and upper sections 10, 11 respectively. By these shoulders the spindle is held against longitudinal displacement.

Mounted adjustably on the cylindrical portion 17' of the spindle 17 behind the shoulders 17³ is a disk 36 having a suitably shaped cam surface 36' substantially as shown in Figs. 5 and 6. This cam serves to regulate the extent of the intermittent stroke to be imparted to the pusher 34. A stationary circular disk 37 mounted on the extension 17' of the spindle 17 adjacent to said first cam 36 and having a cam surface 37' substantially similar in shape to that of the cam surface 36' is provided with a lug 37² projecting laterally therefrom through a circularly curved and concentrically arranged slot 36² provided in the cam 36. This lug 37² is fixed to the cover 11 by screw bolts 38 or otherwise, whereby the cam 37 is held against turning. Keyed to the extension 17' of the worm spindle 17 is a ratchet wheel 39 arranged at the rear of the stationary cam 37.

Rotatively mounted on the extension 17' of the worm spindle 17 is also a substantially cylindrical casing 40 which at its outer end is closed, but which is open on its inner end and is adapted to inclose the said cam 37, ratchet wheel 39 and a part 36³ of the adjustable cam 36. The uncovered or exposed part of said adjustable cam is located between the inner edge of said casing and the rear edges of the upper and lower sections of the casting.

The casing 40 has a hollow peripheral extension 40² from which projects an arm 40³ constituting a crank for the manipulation of the machine. Arranged in the hollow extension 40² of the casing 40 is a roller 41 adapted to coöperate with the cams 36, 37. This roller is rotatively mounted on a pin 42 projecting laterally from a circularly shaped member 43 which is formed with a peripheral extension 43' terminating in a bolt 43² movably supported with its free end in a socket 40⁴ provided in the closed end 40⁵ of the extension 40² of the casing 40. A spiral spring 44 mounted around said bolt is adapted to constantly press the roller 41 against the stationary cam and the member 43 toward the toothed wheel 39. The member 43 is provided with a tooth 43³ which is adapted to periodically engage the ratchet wheel 39 and thereby on rotation of the casing 40 by means of its crank arm 40³ to impart rotary motion to said wheel 39 and consequently to said worm spindle 17 (Figs. 5 and 6).

When the casing 40 is revolved by means of its crank arm 40³ the roller 41 while traveling over the circular part of the periphery of the stationary cam will hold the tooth 43³ of the pawl or member 43 out of the path of the teeth of the ratchet wheel 39 and the worm spindle 17 remains stationary. As soon as the roller reaches the cam surface

37' it, together with the member 43 under the action of the spring 44, is moved toward said cam and wheel, permitting the tooth 43³ to enter the path of the teeth of the 5 ratchet wheel 39 and engage the same. The engagement between the tooth 43³ and the ratchet wheel 39 is effective during the period the roller 41 travels over the cam surface 37' of the disk 37. And during this 10 period while the casing 40 is revolved the worm spindle 17 will be rotated through the medium of the ratchet wheel 39 keyed thereto. The pusher or feeder will be fed during this period and the extent of its intermittent feeding stroke will depend upon the 15 length of the cam shaped portion 37' of the periphery of the stationary cam 37. The slices or pieces of the vegetables or fruit cut will be of uniform thickness corresponding 20 to the individual strokes of the pusher.

In order to allow of a variation in the thicknesses of the pieces to be cut, I employ the adjustable cam 36. This cam normally may be so positioned as to be out of the 25 path of the roller 41. When it is desired to change the individual stroke of the pusher in order to allow of the cutting of thinner or thicker slices or pieces, the cam disk 36 is turned on its axis until its cam surfaces 30 36' projecting beyond that of the stationary cam 37 and the roller 41 will coöperate with said cam 36 instead of with the cam 37, thereby modifying the length of the stroke of the pusher 34.

35 In the present example the two cams 36 and 37 are so shaped that upon adjustment of the cam 36 the cam surface of the other cam 37 will be lengthened or shortened thereby a great variation in the lengths of 40 the stroke of the pusher will be effected.

The adjustable cam disk 36 is provided in the exposed part of its periphery with a plurality of notches 36⁴. In a lug 11² projecting from the upper section 11 of the 45 casting I provide a threaded bore in which works a set screw 45 adapted to engage any one of the notches 36⁴ of the adjustable cam. Thus after the cam 36 has been adjusted for a certain thickness the latter is 50 engaged by the set screw 45 as described and is locked in its adjusted position. The exposed portion of the periphery of the cam disk 36 may be provided with markings 36⁵ which are arranged in accordance with the 55 different adjustments possible and an indicator or pointer 46 directed toward the cam 36 when registering with any one of said markings will indicate to the user the kind of adjustment the machine was set to.

60 The cam 36 is also provided with a peripheral projection or finger 36⁶ whereby it may be conveniently turned around on its axis for the purpose of adjustment.

The shaft 24 extends with its rear end 65 throughout the cylindrical extension 17' of

the worm spindle and projects outwardly therefrom, terminating in a square 24' on which is mounted a collar 46 formed with a lateral lug 46'. This lug is adapted to engage a notch 40' in the hub portion of the 70 casing 40, whereby the shaft 24 is operatively connected to the crank operated casing 40. Thus at all times when the casing is revolved the shaft 24 will revolve while the worm spindle 17 will only periodically 75 receive rotary motion, advancing the pusher intermittently at strokes corresponding to the particular adjustments of the cams 36, 37 relative to one another. With the rotation of the shaft 24 the circular cutter 25 80 will revolve and cut the vegetables or fruit pressed forwardly by the pusher into the path of said cutter to uniform slices or pieces of a certain thickness. Thus, for instance, with the knife 25 only one kind of 85 cuts can be effected, as for instance uniform slices of potatoes, onions, etc.

The socket formed by grooves 22, 23 (Fig. 10) at the open end of the receptacle 12 serves to receive and hold an additional cutter 47 which may be used in coöperation 90 with the circular knife in order to produce cuts of different shape. The knife 47 in size and shape conforms with the socket and is adapted to snugly fit in said socket. 95

In the present embodiment of my invention this cutter 47 consists of an open frame provided with a plurality of parallel blades 48 extending across and in width slightly shorter than the depth of the opening in 100 said frame. The sharp edges of said blades are directly inwardly and are adapted to cut transversely the article when pressed forwardly by the pusher 34, before being acted upon by the rotary knife 25. If the 105 kind of cut desired does not require the knife 47, the latter can be removed from the socket 22, 23 and replaced by an open frame (not shown) substantially of the shape and size as that of the knife 47 but in which the 110 blades 48 are omitted. In this case the article will be fed toward the rotary knife through said open frame.

The return of the feeder or pusher 34 into initial position is effected by the following 115 means:

A bolt or lug 49 is mounted in a support 53 projecting from the casing 40 and has on its inner end a ratchet tooth 49' adapted to engage a notch 17⁴ formed with a catch 120 17⁵. When the casing is turned in a direction opposite to that of the cutting action, the tooth will engage said catch 17⁵ and carry the spindle 17 along, thereby feeding the pusher back in one continuous movement 125 to its original position.

50 denotes a thrust ball bearing for the ratchet wheel 39 which may be suitably mounted in the casing 40 as shown in Fig. 3.

51 denotes a cap screwed on a threaded 130

portion 24² of the shaft and held in position by a set screw 52 for tightening the ring 46 in engagement with the casing 40.

To guard against injury by the rotary 5 knife the top and bottom sections 10, 11 of the casting may be provided with lateral circular extensions or flanges 54, 55 as indicated in Figs. 1 and 2. There may be also attached to the casting a circularly curved 10 guide 56 partly surrounding the circular cutter 25 to guide the cut product falling down through the space between said cutter and the casting into a receptacle 55 which may be placed underneath the cutter.

15 The operation of my cutting machine is as follows:

The vegetables are thrown into the receptacle 12 through the hopper 14, 15 while the pusher 34 is in position at the rear of 20 the hopper. The casing 40 is then turned by means of the crank arm 40³ whereby the pawl 43³ will be caused to periodically engage the ratchet wheel 39 and impart to the 25 spindle intermittent movements depending upon the relative position of the two cams 36 and 37. By this intermittent rotation of the worm 17 the pusher will advance periodically and feed the vegetables toward the knives. If a knife like 47 is used the 30 vegetable will be first cut lengthwise or transversely and then by the rotary knife.

Instead of arranging the blades 48 horizontally the same may be arranged vertically. The knife 25 is shown as provided 35 with two spiral blades. The number of blades is optional. The same may be spaced apart to correspond with the feed of the pusher.

The shape of the cuts to be made may be 40 variegated by providing differently shaped knives and by using the knives 25, 47 and 32 separately or in conjunction with one another.

It is understood that various changes may 45 be made by those skilled in the art without departing from the principle of my invention and I therefore do not wish to restrict myself to the details described and shown.

What I claim and desire to secure by Letters Patent is:—

50 1. In a vegetable cutting machine, the combination with a receptacle and a rotary cutter at one end of said receptacle, of means for imparting rotary motion to said cutter, a pusher in said receptacle, means operatively connected to said first named means to impart intermittent motion to said pusher and cams adjustable relative to one another to lengthen or shorten the stroke of the 55 intermittent movement of said pusher.

60 2. In a cutting machine, the combination with a receptacle and a rotary cutter, of a rotary shaft carrying said cutter, a worm spindle loosely mounted on said shaft, a 65 pusher in said receptacle fed by said worm

spindle, means for revolving said shaft, means operatively connected to said first named means to impart an intermittent movement to said worm spindle and pusher, and means for regulating the extent of said 70 intermittent movement.

3. In a vegetable cutting machine, the combination with a receptacle and a rotary cutter, of a rotary shaft carrying said cutter, a worm spindle loosely mounted on said shaft, a pusher in said receptacle fed by said worm spindle, a ratchet wheel operatively connected to said worm spindle, means for imparting rotary motion to said shaft, a pawl adapted to periodically engage said 80 ratchet wheel to impart intermittent motion to said worm spindle and means for varying the period of such engagement to regulate the extent of said intermittent motion.

4. In a vegetable cutting machine, the combination with a receptacle and a cutting means, of a rotary shaft carrying said means, a pusher in said receptacle, a crank for imparting rotation to said shaft, a worm spindle loosely mounted on said shaft and adapted to move said pusher, a ratchet wheel connected to said worm spindle, a yielding pawl carried by said crank and adapted to periodically engage said ratchet wheel and impart intermittent motion to 90 said worm spindle and pusher, an adjustable cam for controlling the period of engagement of said pawl with said ratchet and the extent of the intermittent stroke of said pusher.

5. In a vegetable cutting machine, the combination with a receptacle and a cutting means, of a rotary shaft carrying said means, a pusher in said receptacle, a crank for imparting rotation to said shaft, a worm spindle loosely mounted on said shaft and adapted to move said pusher, a ratchet wheel connected to said worm spindle, a yielding pawl carried by said crank and adapted to periodically engage said ratchet wheel and impart intermittent motion to 105 said worm spindle and pusher, an adjustable cam, a roller connected to said pawl and adapted to coöperate with said cam to control the period of engagement of said pawl with said ratchet wheel, and means for returning the pusher into initial position in a 110 continuous stroke.

6. In a vegetable cutting machine, the combination with a receptacle and a rotary cutter, of a rotary shaft carrying said cutter, a pusher in said receptacle, movable means on said shaft for feeding said pusher, a ratchet wheel operatively connected to said movable means, means for imparting 120 rotary motion to said shaft, a pawl carried by said last named means, means for causing said pawl to periodically engage said ratchet wheel and impart thereto and to the aforesaid movable means rotation, and 125

means for varying the period of such engagement between said pawl and ratchet to regulate the stroke of the pusher.

7. In a slicing machine, a cutting and feeding mechanism comprising a hollow screw, a knife driving shaft extending therethrough, a knife on one end of the said shaft and a power wheel or crank on the other, and means for intermittently operating said

screw from a continuous rotation of said 10 driving shaft, substantially as and for the purpose set forth.

In testimony whereof I affix my signature in presence of two witnesses.

ADOLF STOLTENBERG.
